UNITED STATES PATENT OFFICE.

HAMILTON LINDSAY, OF WILLOUGHBY, OHIO.

LOCOMOTIVE-STOKER.

1,347,281.

Specification of Letters Patent. Patented July 20, 1920.

Application filed April 9, 1917. Serial No. 160,631.

To all whom it may concern:

Be it known that I, HAMILTON LINDSAY, a citizen of the United States, residing at Willoughby, in the county of Lake and State of Ohio, have invented a certain new and useful Improvement in Locomotive-Stokers, of which the following is a full, clear, and exact description, reference being had to the accompanying drawings.

10 This invention relates to mechanism adapted to feed coal automatically from a locomotive tender into the fire box. The general object of the invention is to provide a mechanism for this purpose which shall be simple in construction and efficient in operation and adapted for ready installation on existing types of locomotives and tenders, without taking up undue space and without interfering with the mutual play 15 of the locomotive and tender while traveling or the convenient uncoupling of them when desired.

20 Another object is to cause comparatively even spreading of the coal over the fire bed by feeding it into the fire box with a sudden tossing action approximating that of hand shoveling. Another object is to insure regularity in the feeding of the desired quantity of proper sized coal from the tender to the devices which throw it into the fire box.

To the above ends I have provided at the fire box front a receptacle into which the coal may be continuously fed, and I cause a throwing blade to periodically engage 25 coal in such receptacle and force it into the fire box. The blade preferably revolves with a variable speed of movement, having its quick action while in engagement with the coal to throw or toss it over the fire bed.

30 In the preferred form, the coal in the tender is caused to drop by gravity through a movable screening grate into a worm conveyer which carries it forward and discharges it into another worm conveyer located below the floor of the cab of the locomotive. This latter conveyer feeds the coal forwardly, and, adjacent to the fire box, directs it upwardly along diverging passageways, which lead to the receptacles in communication with the fire box. In each of 35 these receptacles is one of the revolving, variable speed throwing blades referred to. The throwing blades, the two conveyers, and the movable grate are all preferably

driven by a suitable device on the locomotive, as, for example, a small steam engine located in the cab.

My invention is hereinafter more fully described in connection with a preferred embodiment thereof shown in the drawings, 60 and its essential characteristics are summarized in the claims.

In the drawings, Figure 1 is a side elevation of a locomotive and tender equipped with my automatic stoker; Fig. 2 is a sectional end view of the locomotive equipment looking toward the fire box; Fig. 3 is a side elevation of the apparatus, being sectioned through the locomotive cab and the adjacent portion of the tender; Fig. 4 is a plan of the 65 parts shown in Fig. 3; Fig. 5 is a transverse section substantially on the line 5—5 on Fig. 3, looking toward the fire box; Fig. 6 is a vertical section through one of the hoppers adjacent the fire box, being on a plane 70 parallel with Fig. 3; Fig. 7 is a sectional side elevation of the hopper and throwing blade gears, as indicated by the line 7—7 on Fig. 2; Fig. 8 is a substantially horizontal section through the hopper on the line 8—8 75 of Fig. 6; Fig. 9 is a detail of the worm feed and deflector at the fire box end, being a sectional plan; Fig. 10 is a horizontal section through the feeding device in the tender; Fig. 11 is a detail of the mechanism for 80 rocking the tender grate, being sectioned through the shaft thereof; Fig. 12 is a transverse section through the tender conveyer; Fig. 13 is a perspective of the throwing blade used in either of the receptacles 85 adjacent the fire box; Fig. 14 is a cross section through one of the bearings for the shafts extending into the hoppers.

In the drawings, A indicates a locomotive having a fire box with the usual inclined 90 end B. This fire box has the usual inner sheet B' separated by a water space. C indicates the cab and C' the floor thereof. D indicates the tender having a water space D' and a fuel space D² at the base of which is a 95 floor D³. The exact construction and arrangement of these parts, of course, differs greatly in different installations, and the example shown is to be taken as illustrative of any locomotive and tender to which my 100 stoking mechanism is applicable.

I will first describe the mechanism mounted on the tender to receive the coal and feed

it forward to the locomotive proper. For this, reference should be had to Figs. 1, 2, 3, 4, 10, 11 and 12.

The conveying mechanism for the tender 5 is mounted in a central compartment thereof, which I provide beneath the coal space, by utilizing a part that is ordinarily water 10 space. That is to say, beneath the floor D³ of the tender I provide a suitable vertical wall 10 about the sides and far end of a central space, which is open below and at the end near the locomotive. Within this space I mount a trough 12 secured to the under 15 side of the tender floor. A suitable opening 11 through the floor discharges into this trough. Within the mouth of the trough, substantially on the line of the floor is a rocking grate 13, and within the trough is a worm conveyer 14.

20 The grate and conveyer worm are properly moved to effect a discharge by gravity of coal in the tender into the worm trough, and the forward feeding thereof toward the locomotive. The grate is shown as having 25 trunnions 16 and 17 at its opposite ends, by which it is supported. Suitable means, hereinafter described, act on one of these trunnions to rock the grate to shake coal of proper size regularly into the conveyer 30 trough.

The conveyer worm 14 is shown as having a shaft 20 journaled in bearings adjacent the two ends of the trough. At the rear end the bearings may be carried by the end wall 35 of the trough. At the forward end the trough has an upwardly inclined bottom 15 through which the shaft 20 projects, the bearing 21 at this end being carried on the under side of this inclined bottom. The rotation of the worm 14 and the rocking of 40 the grate results in feeding the coal from the tender forwardly and discharging it at the front end of the trough which is formed into a spout 22 to freely overhang a suitable 45 hopper on the locomotive conveyer.

To rotate the worm, its shaft is provided on the rear end with a gear wheel 24 meshing with a pinion 25 on a shaft 26, which is shown as carried in brackets 27 secured 50 to the sides of the trough. To oscillate the grate I provide its rear trunnion 16 with a pair of depending arms 28 which are adapted to be successively engaged by pins 29 on the gear 24. The pins and arms 28 55 coact after the manner of an anchor escapement. As the pin engages one arm it raises it, sliding under it, tipping the grate upwardly on that side and downwardly on the other side. Then, as the pin engages the opposite arm, the grate is rocked in the opposite direction. As many pins as desired may 60 be used for this purpose on the gear 24. I have shown two pins, giving the grate two complete oscillations for each rotation of 65 the worm.

When the locomotive is traveling there is considerable independence of movement between the locomotive and tender, angularly, vertically and laterally, and, to a certain extent, longitudinally. To provide for this, 70 I couple the driving shaft 26 of the tender conveyer with the driving mechanism, hereinafter described, on the locomotive, by means of universal joints 30 and 31 and an intermediate shaft 32, and I arrange the 75 shaft 26 to be slidable in its bearings 27 and I make the pinion 25 of considerable length, so that the shaft 26 may shift longitudinally, or may change its position bodily with reference to the locomotive, without 80 disturbing the driving connection. For similar reasons the spout 22 of the tender conveyer is not positively connected with the locomotive conveyer, but simply overhangs it and discharges into it. 85

When the tender is to be uncoupled from the locomotive it is only necessary, as far as the stoker is concerned, to uncouple the driving connection to the shaft 26. For this purpose I have made the shaft 32 separable 90 from the universal joint 31, normally connected to it by a pin 33 locked at 34.

The locomotive conveyer, which receives the coal discharged from the tender conveyer and carries it to the receptacles adjacent to the fire box, has a tubular casing 40 located beneath the cab floor C', a suitable hopper 41 discharging into such casing, and a pair of diverging pipes 43 and 44 leading diagonally upwardly on opposite sides of 100 the casing along the front of the fire box and through the cab floor and terminating in the two receptacles 45 and 46. A rotatable worm 50 within the casing 40 feeds the material forward where it is directed by a 105 double-inclined wall 42 into the two branch conduits 43 and 44. Thus a constant supply of coal is maintained in each receptacle.

The worm 50 is mounted on a shaft 51 having bearings in castings closing the opposite ends of the casing 40, the forward casting 47 forming the deflecting walls 42. At the rear end this shaft is provided with a spur gear 54 which meshes with a pinion 55 on the same driving shaft 60 which carries one member of the universal joint 31. Accordingly, the rotation of this shaft rotates the worms of the locomotive conveyer and the tender conveyer in unison. The ratio of the gears driving the worms 14 and 50, as shown, is such that the forward worm moves faster than the rear worm, thus preventing congestion of coal in the conveyer 40. 110

To drive the shaft 60, as well as the throwing blades hereinafter described, I have shown a small steam engine 62 mounted on the end of the fire box and operating a shaft 63. This shaft is shown as connected by a sprocket wheel 64 and a sprocket chain 130

65 with a sprocket wheel 66 on a transverse shaft 67 journaled near the floor of the cab. On this shaft 67 is shown a spur gear 68 meshing with an idler 69 which meshes with 5 a spur gear 70 on a transverse shaft 71 below the floor of the cab. This latter shaft carries a bevel pinion 72 meshing with a bevel pinion 73 on the forward end of the shaft 60.

10 The mechanism above described operates to continuously feed coal upwardly and in regular amount into the receptacles 45 and 46. These receptacles are located along the end of the fire box, being secured to the fire 15 box sheet B by flanges 48. Each receptacle is preferably of the form shown in Figs. 6, 7 and 8, having a bottom 80 with a rectangular opening communicating with the conduit 43 or 44. The receptacle preferably extends 20 upwardly a short distance in a rectangular form, and then has its rear wall rounded away from the fire box, as shown at 81, and then continued upwardly at 82, parallel with the fire box. On the lower portion of its 25 forward side the receptacle is in free communication with the fire box, through an opening in the fire box wall through which coal may be thrown. About this opening the outer and inner sheets B and B' of the 30 fire box are connected by a transverse boiler sheet B², surrounding the opening.

85 indicates a suitable chute leading from the receptacle forwardly through the opening provided into the fire box. This chute 35 may rest on the boiler wall B² and protect it from the coal. The chute preferably has diverging upturned wings 86 to properly direct the coal, which is thrown across the chute into the fire box.

40 To effectively throw coal from the receptacle 45 or 46 through the fire box opening described, so that it will be spread comparatively evenly over the fire bed, I provide a revolving blade 90 within the receptacle 45 which rotates in the direction of the arrow in Fig. 6, and as it swings downwardly and forwardly engages the coal and throws it into the fire box. The blade 90 may be of the form shown particularly in Fig. 13. 50 These blades in the two receptacles are preferably mounted on a single shaft 92 journaled in bearings carried by the side walls of the two receptacles and extending beyond the receptacle 45. At this latter end the 55 shaft carries a gear 93 which meshes with a gear 94 on the shaft 67. This connection causes the blades 90 in the two receptacles to rotate whenever the conveyer mechanism is driven.

60 It is desirable that the blades 90 have a quick action while in engagement with the coal, to toss it into the fire box, and have a slow action while out of engagement therewith, to provide sufficient time for the coal 65 to be fed upwardly by the conveyer. To ac-

complish this I make the gears 93 and 94 elliptical, as shown in Figs. 3 and 7. This gearing gives the blade a slow movement during the upper half of its rotation, during which time the coal is fed upwardly into the 70 space in the receptacles beneath the shaft 92, as indicated at E in Fig. 6. Then, as the blade swings downwardly and forwardly on the lower part of its rotation, it engages the coal on the top of the supply with a quick 75 movement which throws it through the fire box opening onto the fire, as indicated at E'.

On account of the wear encountered by the blade 90, in periodically engaging the coal in the manner described, I reinforce it 80 near its edge by a hardened plate or strip 95 removably bolted to it. Accordingly, this strip may be replaced whenever worn out.

The action of the throwing blade in the receptacle is to toss the coal diagonally upwardly into the fire box. To properly regulate the distance to which it is thus thrown, I provide an adjustable deflector plate 100 in the fire box opening. This deflector plate is connected by suitable arms 101 with a 90 shaft 102 extending across the two receptacles and mounted in bearings in the walls thereof. This shaft extends to the outer side of the receptacle 45 and is there provided with a suitable lever 105 by which it 95 may be turned to position the deflector 100. This lever is shown as provided with a hand grip 106 operating a pawl adapted to engage a stationary segment 108 and thus lock the lever and deflector in any desired position.

To maintain the shaft 92 cool enough so that it will not interfere with the lubrication of its bearings and prevent the blade 90 and deflector plate 100 from being burned 105 by the heat of fire, I arrange the following air passages: The shaft 92 is made hollow, and there are openings 97 between the hoppers 45 and 46 and the ends of the shaft, which permit air to pass inwardly from each 110 side of the hoppers along the interior of this shaft and outwardly through slots 98 onto the throwing blade. The shaft 102 is also made hollow and has similarly arranged openings between the hoppers, and has its 115 ends open at the outer sides of the hoppers so that air may pass into the hoppers from each side through this shaft and out of a slot 103 against the deflector 100. The draft caused by the fire sets up a rapid circulation 120 of air along these hollow shafts into the hoppers from each side thereof and outwardly against the blades 90 and deflectors 100 respectively, thus keeping these parts 125 comparatively cool.

To further insure cool bearings for both of these shafts, I provide bushings 112 tightly held in the bearing members 114 on the sides of the hoppers 45 and 46. These bushings have grooves or flues 115 through 130

which air may pass into the hoppers by reason of the draft. Thus, these bearings are kept comparatively cool and may be satisfactorily lubricated with a semi-solid lubricant carried in a suitable grease cup 116, Fig. 14.

To enable the attendant in the locomotive to observe the action in the receptacles, I make the top of the receptacle in the form 10 of a hinged plate 88, which may be turned up, disclosing the interior. A suitable doorway B³ in the locomotive independently of the receptacles enables observation of the fire bed. This doorway also provides means 15 for originally laying the fire or for feeding by hand in starting the locomotive, or at any time the engine 62 may not be available.

It will be seen that by my mechanism the coal may be fed continuously and automatically from the tender to the fire bed. 20 The attendant occasionally observing the condition of the fire bed through the doorway B³ and the condition of the coal in the receptacles by raising the lids 88, varies the speed of the conveyers according to whether 25 more or less coal is desired, and varies the position of the deflectors 100 from time to time, to properly distribute the coal. The coal in the tender falls automatically onto 30 the shaking grate and it is only necessary for the attendant occasionally to move coal toward the center when the supply runs low.

When sufficient coal has been fed to the fire to last for a time, the feeding may be 35 temporarily discontinued by controlling the mechanism at the grate in any convenient manner. For example, I may merely shut off the steam supply through the pipe 120 leading to the engine 62 by operating a 40 valve 122.

From the foregoing description it is apparent that I have provided a simple automatic stoker which may be conveniently applied to existing locomotive equipment and 45 that I have accomplished the objects previously set forth. Furthermore my device is capable of feeding coal of various grades and size of particles, the advantage of the comparatively large troughs and worms being 50 that a lump of coal may be fed without danger of breaking the parts. I have found by experience that lumps several inches in diameter do not interfere with the movement of coal along the worm troughs in the 55 passage between the shaft of the worm and the casing therefor. The advantage of so arranging the worms as to take care of occasional lumps is that coal of more economical size than the slack, which most stokers must 60 use, may be handled by my stoker.

Having now described my invention, what I claim is:

1. In a locomotive stoker, the combination of means on the locomotive for feeding coal 65 to the fire box, including a conveyer, a

separate conveyer on the tender freely overhanging the conveyer on the locomotive and adapted to feed coal into a position to drop by gravity into the locomotive conveyer and a movable grate on the tender for causing a 70 regulated flow of coal to the tender conveyer.

2. In a locomotive stoker, the combination with throwing means adjacent to the fire box and a conveyer for feeding coal thereto; of a worm conveyer on the tender and adapted 75 to discharge into the conveyer first mentioned, a rocking grate for controlling the gravity feed of coal to said tender conveyer, a gear on the worm of the tender conveyer, means operated thereby for rocking the 80 grate, and a driving shaft having a pinion meshing with said gear.

3. The combination, with a fire box, of a pair of receptacles secured to the end of the fire box side by side and in communication 85 with the fire box, a single conveyer, upward conduits from the conveyer to the end portions of both receptacles, a shaft extending across two receptacles, blades on said shaft within the respective receptacles, and mechanism 90 for rotating said shaft.

4. The combination of a pair of receptacles secured side by side to the end of the fire box and in communication with the interior thereof, a shaft extending through 95 said receptacles and having its bearings on the side walls thereof, a pair of blades on said shaft located within the respective receptacles, mechanism on the shaft for rotating it, a conveyer having a casing, and a 100 pair of diverging conduits leading from the inner end of the conveyer upwardly to the lower ends of the receptacles.

5. In an automatic stoker, the combination of a receptacle in communication with the fire box, a movable blade in said receptacle, means for giving it movement to position the coal into the fire box, a movable deflector in the path of the coal, means for operating said deflector including a shaft, there being a shaft for the blade, both of said shafts being hollow and having openings within the receptacle whereby air may pass along the shafts into the receptacle and outwardly into contact with the blade and deflector respectively.

6. In an automatic stoker, the combination of a receptacle in communication with the interior of a fire box, a movable device in said receptacle controlling the feeding of the coal, a shaft for operating said device having a bearing in the wall of the receptacle, and longitudinal passages surrounding the shaft at the bearing whereby air may pass into the receptacle to keep the bearing cool.

In testimony whereof, I hereunto affix my signature.

HAMILTON LINDSAY.
